CLAIM

The ornamental design for a musical toy with moveable
pieces, as shown and described.

DESCRIPTION

FIG. 1 is a top and front perspective view of the musical toy
with moveable pieces showing my new design;

FIG. 2 is a top and front perspective view similar to FIG. 1
except for the inclusion of broken lines showing the moveable
pieces placed within the correspondingly shaped bases or
within the orchestral pit portion of the musical toy;

FIG. 3 is a top plan view of FIG. 1;

FIG. 4 is a front elevation view of FIG. 1;

FIG. 5 is a rear elevation view of FIG. 1;

FIG. 6 is a right side elevation view of FIG. 1; and,

FIG. 7 is a left side elevation view of FIG. 1.

The broken lines are included for the purpose of illustrating
elements of the musical toy that form no part of the claimed
design.
